INTERNAL COMBUSTION ENGINE AND
METHOD OF OPERATING SAME

Andre J. Meyer, Detroit, Mich., assignor to Continental Motors Corporation, Detroit, Mich., a corporation of Virginia

Application July 27, 1931, Serial No. 553,333

30 Claims. (Cl. 123—81)

My invention relates to internal combustion engines and refers more particularly to the sleeve valve types of engines as distinguished from poppet valve engines, although many features of my invention are adaptable to general types of engines.

In engines and in particular those engines of the sleeve valve type I have discovered that if the fuel mixture is supplied thereto in such a manner as to impart a swirling motion to the fuel mixture that improved results may be obtained. The fuel mixture may be caused to swirl by any suitable means, one of such means being illustrated in Figure 2 which shows a sleeve valve means having an intake port cooperating with the cylinder port in such a manner as to impart a swirling motion to the fuel mixture. In many instances a swirl is intensified by movement of the piston during compression. Obviously means which are located exteriorly or internally of the combustion chamber may be employed as desired for inducing the fuel mixture to swirl. My invention is not limited to an engine of the single sleeve valve Burt-McCollum type as shown in the illustrated embodiments of my invention since my improvements are readily adaptable to other engines such as the Knight type or engines employing reciprocating or rotating sleeve valve means as will be apparent as the description continues.

By swirling the fuel mixture within the combustion chamber it has been found that detonation may be decreased since the swirling of the fuel mixture permits a more efficient dissipation of the heat generated by burning said fuel mixture. It has been found, however, that the swirling of the fuel mixture in the combustion chamber of an engine causes the fuel mixture to become stratified and thus the fuel mixture in the region of the cylinder axis about which the fuel mixture swirls is relatively leaner than the fuel mixture adjacent the cylinder walls due to the fact that the heavier fuel particles are thrown outwardly with respect to the cylinder axis by centrifugal forces.

Usually a sparking device is employed for igniting the fuel charge in the engine and generally this sparking device has been located in such a way as to initially ignite the fuel mixture in the vicinity of the cylinder axis and consequently this relatively lean fuel mixture is burned more rapidly than the relatively rich mixture adjacent the cylinder walls, thus causing a combustion knock. This combustion knock is increased as the speed of the swirling fuel mix-

ture is increased and it has been found that the combustion knock becomes audible and objectionable under certain swirling conditions. Thus I have discovered that the amount of swirl which can be induced to the fuel mixture is limited by the combustion knock tendency of the engine.

It is desirable to induce the fuel mixture to swirl at a greater speed than that amount as limited by the combustion knock tendency and in order to overcome this difficulty I have discovered that if the relatively rich fuel mixture in the vicinity of the cylinder wall or outer peripheral portion of the combustion chamber is initially ignited, that the charge within the engine is burned more slowly and objectionable combustion knock is eliminated or greatly reduced.

Difficulty is sometimes experienced in efficiently igniting the relatively rich rapidly swirling fuel mixture since the time element is in some instances not sufficient to insure a positive ignition of the fuel mixture especially where the amount of swirl is relatively great. This last mentioned problem is overcome by the means shown in the illustrated embodiment of my invention which provides a sparking device so located as to generate a spark in proximity with the relatively richer fuel mixture and the engine is so constructed as to upset the swirl in one embodiment of my invention in the vicinity of the sparking device or other suitable ignition means so as to permit the positive igniting of the relatively rich fuel mixture.

The object of my present invention is to provide novel methods of operating internal combustion engines especially with respect to the fuel mixture burning and to provide novel and improved engine constructions having improved operating characteristics.

Thus I have provided methods and means for burning a swirling fuel mixture in the engine combustion chamber in such a manner as to eliminate objectionable combustion knock in the operation of the engine, improve horse-power output, fuel economy and general engine performance.

A further object of my invention resides in the provision of an engine preferably of the general classes aforesaid wherein the fuel consumption is materially decreased and the engine horsepower materially increased, either of which are constantly striven for in the engine art. Thus I have discovered that by reason of the swirling of the fuel mixture in the combustion chamber, a relatively rich mixture is created around the out-

er portions of the combustion chamber while a relatively lean mixture is formed at the central zone of the combustion chamber. Heretofore in sleeve valve engines it has been customary to position the spark plug at the central zone ordinarily along the general axis of the cylinder and sleeve valve or valves. Now with such arrangement the fuel mixture must be made overly rich in order to obtain ignition of the fuel when the 10 spark plug fires. I have discovered that by locating the spark plug off-center with respect to the cylinder and sleeve axis that I am enabled to operate the engine with a much leaner fuel mixture under which conditions the mixture will 15 properly ignite. Furthermore I have discovered that for a given engine there is a critical position for the spark plug intermediate the cylinder axis and combustion chamber walls where a maximum of fuel economy and power increase 20 is obtainable over common practice heretofore. Broadly speaking, I have discovered that especially in sleeve valve engines the positioning of the spark plug eccentrically or off-center relative to the cylinder axis has decided advantages in 25 fuel economy, power output, and generally improved engine performance.

This application is a continuation in part of my application Ser. No. 531,961 filed April 22, 1931. As one modification embodied herein I 30 have illustrated my invention in connection with an engine embodying the principles and advantages of my combustion chamber as disclosed in my copending application Ser. No. 548,796 filed July 6, 1931. 35 Further objects and advantages of my invention will be apparent as this specification progresses.

For a more detailed understanding of my invention, reference may be had to the accompanying drawings which illustrate several forms 40 which my invention may assume similar reference characters indicating corresponding parts, and in which:

Figure 1 is a vertical sectional view of an internal combustion engine constructed in accordance with my invention,

Figure 2 is a detail sectional view illustrating the means for inducing the fuel mixture to swirl in an engine of the sleeve valve type,

Figure 3 is a modified form of my invention, 50 illustrating a typical cylinder and associated parts of the engine in cross-section,

Figure 4 is a like view illustrating a further modified form of my invention, and

Figure 5 is a diagrammatic chart illustrating the fuel economy and power output plotted 55 against spark plug location.

My invention is adapted for use with an engine of the sleeve valve type as shown in the accompanying drawings which in general consists of a cylinder block 10 having a cylinder 11 and provided with intake and exhaust ports 12 and 13 respectively. A cylinder head structure 14 is secured to said cylinder block and is preferably provided with a depending cylinder head portion 15 which is shown as depending within the cylinder and spaced therefrom to provide a sleeve pocket 16 adapted for receiving the upper end of the sleeve valve means 17, said sleeve 60 valve means being provided with suitable intake and exhaust ports 18 and 19 respectively. The ports 12 and 13 are preferably located below the cylinder head 14 as illustrated, whereby the combustion chamber referred to hereinafter is closed. 70 This arrangement is beneficial in promoting fuel

5 mixture swirl in the combustion chamber, facilitating the combustion process, and in being otherwise desirable in connection with my invention. The illustrated embodiment of my invention shows a sleeve valve means of the Burt-McCollum type wherein a single sleeve is given a combined reciprocating and oscillating movement with respect to the cylinder and sleeve axis whereby any point on said sleeve traverses a closed path. Obviously the scope of my present 10 invention is not limited to the specific type of sleeve valve means shown in the accompanying drawings.

15 The cylinder head is provided with a main combustion chamber zone 20 (20a in Figure 3 and 20b in Figure 4) located concentrically with the cylinder axis and a piston 21 of usual construction operates within the sleeve valve means and may be adapted to be connected with the crankshaft (not shown) in the usual manner by means of a connecting rod 21. Obviously the means for operating the sleeve valve means forms no part of the present invention and it may be understood that any suitable well known type of sleeve driving means may be employed.

20 The construction herein illustrated provides 30 cooperating cylinder and sleeve intake ports 12 and 18 respectively which are arranged to impart a swirling motion to the fuel mixture with respect to the cylinder axis A. In Figure 2 the sleeve is moved during the intake cycle in the direction as indicated by the arrow 22 and the fuel mixture is admitted through the opening 23 bounded by the opening edges 24 and 25 of the cylinder and sleeve valve ports 12 and 18 respectively. This fuel on being admitted through this opening 23 is directed in a direction as indicated by the arrow 26 and is thus caused to swirl with respect to the cylinder axis.

35 Preferably the engine as shown in Figure 1 is so constructed as to induce the fuel mixture to swirl at a relatively high angular velocity which under normal operating conditions will be burned in such a way as to produce an objectional combustion knock. In order to eliminate this objectionable combustion knock, I have provided a construction which is arranged to ignite the fuel mixture charge in such a way as to initially ignite that portion of the charge which is relatively 40 rich. This is accomplished by providing an ignition chamber 30 in the cylinder head which is offset with respect to the cylinder axis and the zone containing the relatively lean fuel mixture.

45 Preferably this ignition chamber is located near the outer peripheral portion of the combustion chamber 20 and the restricted opening or passage 31 connects the ignition chamber 30 with the combustion chamber 20. A sparking device such as a spark plug 32 is assembled with the engine and arranged to position the spark points 33 50 within the ignition chamber and as close to the communicating passage 31 as possible. In this manner the spark plug is off-set from the cylinder axis with the advantages heretofore set forth and hereinafter described in further detail in connection with Figures 3, 4 and 5. During the compression stroke of the engine the swirling fuel mixture is compressed and a portion of the compressed fuel mixture charge is forced into the ignition chamber 30 in such a manner as to upset 55 the swirl in the vicinity of the spark points 33. This fuel mixture in the ignition chamber is in a highly turbulent state and is isolated from the swirling fuel mixture in the combustion chamber and may be very readily ignited especially where 60

the swirl is relatively great so as to give rise to difficulties in proper ignition of the fuel mixture. I am thereby enabled to use to advantage swirl velocities heretofore considered impractical chiefly because of the usual attendant difficulties of combustion knock and failure of the spark plug to ignite the fuel mixture. With a highly swirling fuel mixture the spark tends to be blown out before the fuel mixture is ignited.

10. It will be noted that the spark points are so located with respect to the passage 31 that the incoming fuel mixture is impinged on the spark points thus tending to keep the same clean and eliminate the tendency of carbon forming on said points.

15. On igniting the fuel mixture charge in the ignition chamber 30 it will be noted that the relatively small isolated fuel mixture charge therein is caused to be thoroughly ignited before the burning charge is injected into the combustion chamber 20. In fact, the pressure generated in the ignition chamber is built up considerably before the flame is forced through the passage 31 into the said combustion chamber and it has 20. been found that this jet of flame will positively ignite the rich fuel mixture with which it comes in contact even though the same is swirling at a relatively great maximum velocity.

25. It will be thus noted that I have provided improved methods and means for operating the engine to ignite the fuel mixture in such a way as to cause the same to burn without producing an objectionable combustion knock. Furthermore, with the construction herein illustrated, I find that I may supply a fuel mixture in such a way as to cause the same to swirl with a maximum velocity thereby obtaining all the benefits which have been found to result from swirling the fuel mixture within the combustion chamber.

30. The means and methods by which the above advantages are accomplished are simple in construction and may be readily adapted for use with any type of engine including engines of the single sleeve valve type and those engines which 35. employ other types of valve means such as with engines having reciprocating sleeve valve means as for example valve means of the Knight type.

35. Referring now to Figure 3 I have shown a further embodiment of my invention wherein the spark plug 32a has its terminals 33a extending into the combustion chamber zone or portion 27 in cylinder head 14a. I have illustrated the combustion chamber of the general construction disclosed in my copending application aforesaid 40. wherein the zone 27 constitutes the neck of the generally bottle shaped chamber and 20a the main body portion or zone. The body portion 20a and the neck portion 17 are connected by the walls of the combustion chamber through an 45. inwardly offset portion 20b of the combustion chamber walls as illustrated. The portions 20a and 17 are preferably substantially cylindrical, particularly the portion 20a, in order to realize the maximum amount of offset between the portions 20a and 17 and to promote swirl of the fuel mixture in portion 20a. The cylinder head depending portion 15 preferably has a lower annulus 15a surrounding the chamber portion 20a adjacent the sleeve valve 17, the annulus 15a overlying the face of piston 21 preferably remote from 50. the center of the piston face. The annulus 15a, together with the piston 21 and sleeve valve 17 provides an annular combustion chamber portion 15c communicating with the body portion 20a. This body portion is preferably arranged

co-axially with the piston to promote swirl of fuel mixture therein. In Figure 3 this combustion chamber zone 27 has its axis x^1-x^1 offset an amount O^1 from the axis Y^1-Y^1 of the cylinder 5. if, the spark plug 32a preferably lying along axis x^1-x^1 as illustrated.

10. The wall 20c, of the combustion chamber portions 20a and 27 of Fig. 3, adjacent spark plug 32a in the direction of the spark plug from the cylinder axis Y^1-Y^1 preferably extends substantially vertically upwardly from the annulus 15a whereby to permit the relatively large amount of offset O^1 for the spark plug. It is customary heretofore to provide upwardly and inwardly tapering combustion chamber walls for sleeve valve 15. engines but such constructions necessarily locate the spark plug closely to the cylinder axis. The combustion chambers of Figs. 1 and 4 are similarly constructed with substantially vertical walls adjacent the spark plug.

20. In Figure 4 the cylinder head 14b has its combustion chamber or main zone 20b of substantially cylindrical form as in Figure 1, the spark plug 32b lying on axis x^2-x^2 offset at O^2 from the cylinder axis Y^2-Y^2 . The spark plug 32b has its 25 terminals 33b extending into the combustion chamber 20b as in Figure 3 without the provision of the igniting chamber 30 of Figure 1.

25. Figure 1 likewise has its spark plug 32 offset from the cylinder axis $Y-Y$ by an amount O , the 30 spark plug lying along the axis $x-x$.

30. I have discovered that the off-set spark plug disclosed in Figures 1, 3 and 4 is of great advantage in engines particularly of the sleeve valve type which offer excellent constructions of combustion chamber shaping, location, and swirl of the fuel mixture, such chambers not being hampered by poppet valves or extended chambers as in the common L-head engines. Thus I have 35. found that in usual sleeve valve practice where 40. the spark plug is located axially of the cylinder, the swirl experienced in such engines causes a dense mixture away from the swirl axis and a lean mixture at the axis, it being customary to provide a mixture sufficiently rich so that it will 45. fire properly at the lean portion along the swirl axis. I have discovered that by offsetting the spark plug to a location where it is subjected to the relatively rich fuel mixture, such fuel mixture may be supplied to the engine considerably 50. leaner than customary without sacrificing power and general engine performance. In fact I have determined that with such relatively leaner mixture supply the power delivered by the engine may be increased and in such instances not requiring 55. the igniting chamber 30 of Figure 1 although such chamber may be used to advantage as set forth hereinbefore especially for relatively great amounts of swirl. Thus in Figures 1, 3 and 4 I have illustrated typical examples of my invention with the offset spark plug and in Figures 3 and 4 the embodiments disclosed therein do not utilize the igniting chamber.

60. I have been able in an engine of $4\frac{1}{2}$ inch bore to utilize swirl velocities of 10,000 R. P. M. and in some instances 18,000 R. P. M. of the fuel mixture in the combustion chamber but at the higher ranges of swirl there is a tendency of the fuel mixture to quench the spark. At the upper 65. ranges of swirl velocity, especially in excess of 10,000 R. P. M. my Figure 1 embodiment will be found especially desirable and I contemplate utilizing swirl velocities even in excess of 18,000 R. P. M. 70. 75.

I have discovered by a series of experiments in locating the spark plug at varying distances from the cylinder axis that there is a critical location in a given engine for the amount of off-set where there is a marked increase in power output with a marked decrease in fuel consumption. In other words at such favorable location the fuel mixture may be leaned considerably without a sacrifice of power and in Figure 3 this may be utilized to additional benefits in combination with the generally bottle-shaped chamber 20a, 21 for reducing engine knocking under relatively high compression. Thus zone 21 offers an initial reduction to the rate of pressure rise for the combustion chamber as a whole, as distinguished from a combustion chamber concentrated around the terminals of the spark plug so that the flame curtain may rapidly spread to all parts of the combustion chamber. This slowing down of the fuel mixture burning as a whole by delaying the initial burning is more particularly set forth and claimed per se in my copending application hereinbefore set forth.

Referring to Figure 5 I have illustrated a chart for horse-power at curve 28 and fuel consumption at curve 29, the vertical axis representing the cylinder axis and the horizontal axis representing the distance at any point for the spark plug location from the cylinder axis and the axial center of swirl. The vertical axis also represents values for horse-power and fuel consumption although these are not specifically evaluated as they vary for a given engine. The line designated as 82% represents the most favorable or critical location for the particular engine tested resulting in a distance O³ for spark plug eccentricity, this distance being carried over to Figures 1, 3 and 4 as O, O¹, and O² respectively.

I desire it understood that it is not essential to locate the spark plug at the critical 82% position to realize important advantages of my invention.

In general my experiments have indicated that with the spark plug located approximately 82% of the distance from the cylinder axis to the side walls of combustion chambers 20, 20a, 20b of Figures 1, 3 and 4 respectively offers the best advantages. Theoretically the best location for the spark plug would be substantially 100% of such distance or a full amount of off-set but mechanical difficulties of spark plug size, location, etc., and a certain amount of disturbance created by the swirling fuel mixture at the side walls of the combustion chamber and at the spark plug terminals indicate as a matter of practice that the most favorable position is generally as aforesaid.

In each of the embodiments of my invention the fuel mixture is preferably caused to swirl about the cylinder axis, the upward movement of the piston ordinarily tending to accentuate the swirl as the fuel mixture is compressed above the piston. It will be noted that in each of the embodiments, the combustion chambers are located entirely above the pistons as distinguished from the well known poppet valve types of combustion chambers offset laterally of the cylinder.

It will be apparent to those skilled in the art to which my invention pertains that various methods and constructions disclosed therein without departing from the spirit of my invention or from the scope of the appended claims.

What I claim as my invention is:

1. In an internal combustion engine, a cylinder, a cylinder head structure closing one end of

said cylinder and depending therewithin to provide a sleeve pocket, a single sleeve valve of the combined movement type operable within said cylinder and having its upper end positioned in said sleeve pocket, said cylinder and sleeve valve having cooperating intake and exhaust ports operable below said cylinder head structure, a piston within said sleeve valve, said cylinder head having a combustion chamber in the depending portion thereof adapted to receive a fuel mixture in a swirling condition, and a spark plug for igniting the charge in said combustion chamber, said spark plug being positioned eccentrically with respect to the cylinder axis away from the relatively lean portion of the fuel mixture produced by the swirling motion thereof, said combustion chamber having a substantially vertical wall adjacent the spark plug in the direction of spark plug eccentricity from the cylinder axis.

2. In an internal combustion engine, a cylinder, a cylinder head structure closing one end of said cylinder and depending therewithin to provide a sleeve pocket, a single sleeve valve of the combined movement type operable within said cylinder and having its upper end positioned in said sleeve pocket, said cylinder and sleeve valve having cooperating intake and exhaust ports operable below said cylinder head structure, a piston within said sleeve valve, said cylinder head having a combustion chamber in the depending portion thereof adapted to receive a fuel mixture in a swirling condition, and a spark plug for igniting the charge in said combustion chamber, said spark plug being positioned eccentrically with respect to the cylinder axis away from the relatively lean portion of the fuel mixture produced by the swirling motion thereof, said combustion chamber having a substantially vertical wall adjacent the spark plug in the direction of spark plug eccentricity from the cylinder axis.

3. In an internal combustion engine, a cylinder, a cylinder head structure closing one end of said cylinder and depending therewithin to provide a sleeve pocket, a single sleeve valve of the combined movement type operable within said cylinder and having its upper end positioned in said sleeve pocket, said cylinder and sleeve valve having cooperating intake and exhaust ports, a piston within said sleeve valve, said cylinder head having a combustion chamber in the depending portion thereof adapted to receive a fuel mixture in a swirling condition, and a spark plug for igniting the charge in said combustion chamber, said spark plug being positioned eccentrically with respect to the cylinder axis away from the relatively lean portion of the fuel mixture produced by the swirling motion thereof, said combustion chamber having an offset portion at said spark plug positioned eccentrically with respect to the cylinder axis, said combustion chamber portion having its axis substantially in coincidence with the axis of said spark plug and restrictedly communicating with the combustion chamber.

4. In an internal combustion engine of the sleeve valve type, a cylinder, a piston in said cylinder, sleeve valve means associated with said cylinder, a cylinder head having a portion thereof within said cylinder and having a closed combustion chamber lying directly above the piston, said combustion chamber having a restricted portion positioned eccentrically with respect to the

axis of said cylinder, and a spark plug for said portion.

fuel mixture in said combustion chamber can subsequently be ignited.

5. In an internal combustion engine of the sleeve valve type, a cylinder, a piston, sleeve valve means associated with the cylinder, means providing a closed combustion chamber lying directly above said piston and adapted to receive a fuel mixture in a swirling condition, said combustion chamber having a portion thereof constructed to initially reduce the rate of pressure rise for the combustion chamber as a whole, and a spark plug associated with said combustion chamber portion and positioned eccentrically with respect to the axis of fuel mixture swirl in the combustion chamber.

sequently be ignited.

10. In an engine, a cylinder, a piston, a cylinder head, said piston and cylinder head providing a combustion chamber lying wholly above the piston, means for supplying a fuel mixture to the combustion chamber in such a manner as to impart a swirling motion thereto with respect to the cylinder axis and causing said fuel mixture to become stratified, an ignition chamber offset from said cylinder axis and having an orifice

6. In an engine, a cylinder, a piston, a cylinder head, said cylinder head and piston providing a combustion chamber, means for supplying a fuel mixture to the combustion chamber in such a manner as to impart a swirling motion thereto with respect to the cylinder axis and causing said fuel mixture to become stratified, ignition means associated with said combustion chamber and remotely located with respect to the cylinder axis in proximity with a relatively richer fuel mixture strata, and means for upsetting the swirl in the vicinity of the ignition means, said combustion chamber lying directly above said piston.

said cylinder axis and having an orifice for connecting the said ignition chamber with said combustion chamber, said ignition chamber being adapted to isolate a portion of said relatively richer fuel mixture and remove same from the influence of said swirl, and a sparking device located within said ignition chamber for igniting said isolated fuel mixture from which the swirling fuel mixture in said combustion chamber can subsequently be ignited, said sparking device having spark points adjacent to said orifice whereby said spark points are subjected to the action of the fuel mixture flowing into said ignition chamber during the compression stroke of the engine to maintain said points free of carbon. 25

30 7. In an engine, a cylinder, a piston, a cylinder head, said piston and cylinder head providing a combustion chamber positioned directly above the piston, means for supplying a fuel mixture to the combustion chamber in such a manner as to impart a swirling motion thereto with respect to the cylinder axis and causing said fuel mixture to become stratified, ignition means associated with said combustion chamber and remotely located with respect to the cylinder axis in proximity with a relatively richer fuel mixture strata, and means isolating a portion of said relatively richer fuel mixture and removing same from the influence of said swirl, said isolated portion adapted to be ignited by said ignition means.

35 8. In an engine, a cylinder, a piston, a cylinder head, said piston and cylinder head providing a combustion chamber positioned directly above the piston, means for supplying a fuel mixture to the combustion chamber in such a manner as to impart a swirling motion thereto with respect to the cylinder axis and causing said fuel mixture to become stratified, ignition means associated with said combustion chamber and remotely located with respect to the cylinder axis in proximity with a relatively richer fuel mixture strata, and means isolating a portion of said relatively richer fuel mixture and removing same from the influence of said swirl, said isolated portion adapted to be ignited by said ignition means.

40 9. In an engine, a cylinder, a piston, a cylinder head, said piston and cylinder head providing a combustion chamber positioned directly above the piston, means for supplying a fuel mixture to the combustion chamber in such a manner as to impart a swirling motion thereto with respect to the cylinder axis and causing said fuel mixture to become stratified, ignition means associated with said combustion chamber and remotely located with respect to the cylinder axis in proximity with a relatively richer fuel mixture strata, and means isolating a portion of said relatively richer fuel mixture and removing same from the influence of said swirl, said isolated portion adapted to be ignited by said ignition means.

11. In a sleeve valve engine having a cylinder, a cylinder head having a reentrant portion provided with a combustion chamber, sleeve valve means associated with said cylinder, means for supplying a fuel mixture to said cylinder in such a manner as to impart a swirling motion thereto in said combustion chamber with respect to the cylinder axis and causing said fuel mixture to become stratified, ignition means associated with said combustion chamber and remotely located with respect to the cylinder axis in proximity with a relatively richer fuel mixture strata, said combustion chamber having a wall extending substantially vertically upward from the bottom of said re-entrant cylinder head portion adjacent 40 said ignition means. 30 35

45 8. In an engine, a cylinder, a piston, a cylinder head, said piston and cylinder head providing a combustion chamber positioned directly above the piston, means for supplying a fuel mixture to the combustion chamber in such a manner as to impart a swirling motion thereto with respect to the cylinder axis and causing said fuel mixture to become stratified, an ignition chamber communicating with said combustion chamber and offset from said cylinder axis, said ignition chamber being adapted to isolate a portion of said relatively richer fuel mixture and remove same from the influence of said swirl, and ignition means arranged to ignite said isolated portion of the fuel mixture.

50

55

12. In an engine of the sleeve valve type, a cylinder, a piston, a cylinder head, said head and piston forming a combustion chamber, fuel mixture ignition means, said cylinder head having a portion depending within said cylinder providing a bottle shaped combustion chamber, the neck portion of said bottle shaped combustion chamber being offset from the axis of said cylinder, said ignition device being located at said neck portion. 45 50

60 9. In an engine, a cylinder, a piston, a cylinder
head, said piston and cylinder head providing a
combustion chamber positioned directly above
the piston, means for supplying a fuel mixture
to the combustion chamber in such a manner as
to impart a swirling motion thereto with respect
to the cylinder axis and causing said fuel mixture
to become stratified, an ignition chamber offset
from said cylinder axis and having an orifice for
connecting the said ignition chamber with said
combustion chamber, said ignition chamber being
adapted to isolate a portion of said relatively
richer fuel mixture and remove same from the
influence of said swirl, and a sparking device

70 said isolated fuel mixture from which the swirling
75

13. In an engine of the sleeve valve type, a cylinder, a piston, a cylinder head, said head and piston forming a combustion chamber, fuel mixture ignition means, said cylinder head having a portion depending within said cylinder providing a bottle shaped combustion chamber, having as component parts thereof a neck portion and an enlarged body portion communicating with the neck portion, said neck portion being offset from the axes of said cylinder and said body portion, said ignition device being located substantially at the top of said neck portion. 55 60

14. In an engine of the sleeve valve type, a cylinder, a piston, a cylinder head, said head and piston forming a combustion chamber, fuel mixture ignition means, said cylinder head having a portion depending within said cylinder providing a bottle shaped combustion chamber, having as component parts thereof a neck portion and an enlarged body portion communicating with the neck portion, said neck portion being offset from the axes of said cylinder and said body portion, said ignition device being located substantially at the top of said neck portion, said piston bounding

the combustion chamber at the bottom of said body portion.

15. An engine of the sleeve valve type having in combination a cylinder and piston associated therewith, a cylinder head depending within said cylinder, sleeve valve means operable between the cylinder and the depending portion of the cylinder head, a spark plug carried by the cylinder head, said piston, sleeve valve means and cylinder head cooperating to provide a combustion chamber extending generally longitudinally of the cylinder, said combustion chamber having a zone at the spark plug and a second zone restrictedly communicating with said first zone for minimizing tendencies toward roughness in the engine during the combustion cycle thereof, said spark plug zone being offset from the cylinder axis.
16. An engine of the sleeve valve type having in combination a cylinder and piston associated therewith, a cylinder head depending within said cylinder, sleeve valve means operable between the cylinder and the depending portion of the cylinder head, a spark plug carried by the cylinder head, said piston having valve means and cylinder head cooperating to provide a combustion chamber, said combustion chamber having a restricted zone at the spark plug and a second zone relatively unrestricted communicating with said first zone for minimizing tendencies toward roughness in the engine during the combustion cycle thereof, said zones being located within said depending portion of the cylinder head, said spark plug zone being offset from the cylinder axis.
17. In an engine, a cylinder, sleeve valve means associated with the cylinder, a cylinder head structure for the outer end of said cylinder, said cylinder head having a portion depending within said cylinder and sleeve valve means, said cylinder head and piston cooperating to provide a combustion chamber substantially entirely overlying said piston, said combustion chamber having an inner body portion and an outer neck portion, the wall of said combustion chamber intermediate said inner and outer portions being inwardly offset, and ignition means at said outer neck portion, said neck portion being offset from the cylinder axis.
18. In an engine, a cylinder, sleeve valve means associated with the cylinder, a cylinder head structure for the outer end of said cylinder, said cylinder head having a portion depending within said cylinder and sleeve valve means, said cylinder head and piston cooperating to provide a combustion chamber substantially entirely overlying said piston, said combustion chamber having an inner body portion and an outer neck portion, the wall of said combustion chamber intermediate said inner and outer portions being inwardly offset, and ignition means at said outer neck portion, said inner body portion being substantially cylindrical, said neck portion being offset from the cylinder axis.
19. In an engine, a cylinder, sleeve valve means associated with the cylinder, a cylinder head structure for the outer end of said cylinder, said cylinder head having a portion depending within said cylinder and sleeve valve means, said cylinder head and piston cooperating to provide a combustion chamber substantially entirely overlying said piston, said combustion chamber having an inner body portion and an outer neck portion, the wall of said combustion chamber intermediate said inner and outer portions being

inwardly offset, and ignition means at said outer neck portion, said inner body portion being substantially cylindrical and coaxial with said piston, said neck portion being offset from the cylinder axis.

20. In an engine, a cylinder, sleeve valve means associated with the cylinder, a cylinder head structure for the outer end of said cylinder, said cylinder head having a portion depending within said cylinder and sleeve valve means, said cylinder head and piston cooperating to provide a combustion chamber substantially entirely overlying said piston, said combustion chamber having an inner body portion and an outer neck portion, the wall of said combustion chamber intermediate said inner and outer portions being inwardly offset, and ignition means at said outer neck portions, said outer neck portion being substantially cylindrical, said neck portion being offset from the cylinder axis.

21. In an engine, a cylinder, sleeve valve means associated with the cylinder, a cylinder head structure for the outer end of said cylinder, said cylinder head having a portion depending within said cylinder and sleeve valve means, said cylinder head and piston cooperating to provide a combustion chamber substantially entirely overlying said piston, said combustion chamber having an inner body portion and an outer neck portion, the wall of said combustion chamber intermediate said inner and outer portions being inwardly offset, and ignition means at said outer neck portion, said inner and outer portions being substantially cylindrical, said neck portion being offset from the cylinder axis.

22. In an engine, a cylinder, sleeve valve means associated with the cylinder, a cylinder head structure for the outer end of said cylinder, said cylinder head having a portion depending within said cylinder and sleeve valve means, said cylinder head and piston cooperating to provide a combustion chamber substantially entirely overlying said piston, said combustion chamber having an inner body portion and an outer neck portion, the wall of said combustion chamber intermediate said inner and outer portions being inwardly offset, and ignition means at said outer neck portion, said depending portion of the cylinder head forming an annular combustion chamber portion overlying said piston and communicating with said body portion, said neck portion being offset from the cylinder axis.

23. In an engine, a cylinder, a piston, a cylinder head, said piston and cylinder head cooperating to form a combustion chamber substantially entirely above the piston, said combustion chamber having neck and body portions connected by an inwardly offset portion of the combustion chamber wall, said neck portion being offset from the cylinder axis.

24. In an engine, a cylinder, a piston, a cylinder head, said piston and cylinder head cooperating to form a combustion chamber substantially entirely above the piston, said combustion chamber having neck and body portions connected by an inwardly offset portion of the combustion chamber wall, said cylinder head providing an annular combustion chamber portion overlying said piston and communicating with said combustion chamber portions, said neck portion being offset from the cylinder axis.

25. In an engine, a cylinder, a piston, a cylinder head, said piston and cylinder head cooperating to form a combustion chamber substantially entirely above the piston, said combustion

chamber having neck and body portions connected by an inwardly offset portion of the combustion chamber wall, and a spark plug for said neck portion, said neck portion being offset from the cylinder axis.

26. In an engine, a cylinder, a piston, a cylinder head, said piston and cylinder head cooperating to form a combustion chamber substantially entirely above the piston, said combustion chamber having neck and body portions connected by an inwardly offset portion of the combustion chamber wall, said cylinder head providing an annular combustion chamber portion overlying said piston and communicating with said combustion chamber portions, and a spark plug for said neck portion, said neck portion being offset from the cylinder axis.

27. In an engine of the sleeve valve type, a cylinder, a cylinder head having a portion depending within said cylinder and providing a combustion chamber, sleeve valve means between said head and cylinder, a piston operable within said cylinder below said combustion chamber, said cylinder having its intake and exhaust ports located below said cylinder head, said depending portion of said cylinder head having an annular portion adjacent said sleeve valve means and overlying the periphery of the face of said piston, a spark plug offset from the axis of said cylinder and lying substantially vertically above the inner edge of said annular portion of the cylinder head.

28. In an engine of the sleeve valve type, a cylinder, a cylinder head having a portion depending within said cylinder and providing a combustion chamber, sleeve valve means between said head and cylinder, a piston operable within said

cylinder below said combustion chamber, said cylinder having its intake and exhaust ports located below said cylinder head, said depending portion of said cylinder head having an annular portion adjacent said sleeve valve means and overlying the periphery of the face of said piston, a spark plug offset from the axis of said cylinder, said combustion chamber having a wall extending substantially vertically upwardly from the inner edge of said annular portion of the cylinder head to said spark plug, said wall being spaced from the cylinder axis in the direction of said spark plug.

29. In an engine of the sleeve valve type, a cylinder, a cylinder head, said cylinder having its inlet and outlet ports below said cylinder head, a piston, said cylinder head and piston providing a combustion chamber overlying the piston, sleeve valve means associated with said cylinder, said combustion chamber having a substantially cylindrical portion concentric with the cylinder axis to promote swirl about said axis, and a spark plug positioned above the wall of said cylindrical portion.

30. In an engine of the sleeve valve type, a cylinder, a cylinder head, said cylinder having its inlet and outlet ports below said cylinder head, a piston, said cylinder head and piston providing a combustion chamber overlying the piston, sleeve valve means associated with said cylinder, said combustion chamber having a substantially cylindrical portion concentric with the cylinder axis to promote swirl about said axis, and a spark plug having its terminals positioned closely adjacent the wall of said cylindrical portion.
